P., W. S. & J. J. HENCH.
MILL FOR GRINDING SUMAC.

No. 10,452.

Patented Jan. 24, 1854.

UNITED STATES PATENT OFFICE.

PETER HENCH, W. S. HENCH, AND J. J. HENCH, OF PORT ROYAL, PENNSYLVANIA.

MILL FOR GRINDING SUMAC.

Specification of Letters Patent No. 10,452, dated January 24, 1854.

To all whom it may concern:

Be it known that we, PETER HENCH, W. S. HENCH, and J. J. HENCH, of Port Royal, in the county of Juniata and State of Pennsylvania, have invented certain new and useful Improvements in Modes of Grinding Sumac, and that the following is a full, clear, and exact description of the principle or character which distinguishes it 10 from all other things before known and of the usual manner of making, modifying, and using the same.

Much difficulty has heretofore been experienced in grinding sumac for the market 15 to reduce it to fine impalpable powder, and assort the different qualities, and grind it fine enough; and it has always been attended with great loss, filling the mill with dust, and making the labor of attending it 20 very great; and by all the apparatus heretofore used, a small quantity could be ground, compared to the power expended, so that eight or nine hundred pounds a day was all that could be effected in one machine, re- 25 quiring the constant labor of a man, while in our machine, with less expenditure of power, more than double the work can be accomplished with the attention of a boy only a part of the time, and entirely remov- 30 ing the annoyance of dust; and further, the material has never been ground to the quality of the Sicily sumac, which brings about eighty dollars per ton, while the American article often sells for forty, from its inferior 35 manufacture.

Our apparatus employed is constructed as follows:

An outer case (a) is made of cylindrical form above, but with its under side projected downward, and gathered toward a spout or spouts (b); below, within the cylindrical part of this outer shell or case, there is a door (c'), and on the top an oblong opening (c), to introduce the material 40 to be ground into the inner cylinder (e) and a pipe (d) also for introducing the material down to the center of the cylinder (a) and into an inner cylinder (e) concentric with the circle of the outer case. Within 45 the case is the above named cylinder, marked (e); it turns on a horizontal shaft (f) in bearings (f') in the case, driven by 50 any power convenient. This inner cylinder

(e) is constructed as follows—there are a series of stout staves (e') affixed to the two 55 heads of the cylinder, with spans about equal to their breadth between them; these are lined with an entire cylinder of sheet iron, in which, between the staves, holes are punched for a purpose to be pres- 60 ently described. These staves can be grooved, and receive others when required between them, which we call slip-staves; when said slip-staves are inserted, the cylinder is entirely closed at one point, when a 65 slip stave (e') can be removed, leaving a long aperture (e²) into the interior of the cylinder for charging it; within this cylinder are spikes, or small projections inserted 70 at the points where the permanent staves are; and between the perforated iron portions there is a cylindrical roller (f²) placed within the cylinder, armed also with small 75 projecting points, and having a projecting flanch upon which it rolls; this roller ex- tends from end to end of the cylinder, and serves to grind the sumac which is placed 80 therein, the finer portions of which are constantly sifted out through the openings be- 85 tween the staves. In this operation the and sold to tanners. Around this cylinder 90 (e) we can form another (g), which is close, and revolves with it on the same shaft; in this outer cylinder we place a number of iron balls, weighing say some 75 lbs. more or 95 less, there being sufficient space between the two to permit them freely to pass; this outer cylinder receives the powdered sumac as it is sifted through from the inner one, and there it is ground to a fine powder by the 95 balls, when it is discharged, fit for use.

A modification of this mill shown in the reduced figures is to place the close cylinder on another shaft, and conveying the coarsely powdered material into it by ele- 100 vators. We do not claim the grinding by balls as that has long been known but not in conjunction with a roller in the manufacture of sumac, which is necessary to detach and partially pulverize and sift the material be- 105 fore carrying it to the balls.

What we desire to secure by Letters Patent is—

The employment of a cylinder (*e*) having projecting points or teeth on its internal 5 surface with a roller having heads on its ends on which it rolls and is kept above said teeth, said roller also having teeth projecting from its surface interlocking with those first named on the cylinder by which the 10 better portions of the sumac are beaten off

and passing through the apertures in the cylinder enter another where they are ground fine as described.
